UNITED STATES PATENT OFFICE

125,106

DESIGN FOR A TEXTILE FABRIC

Harvey E. Kivelson, Lawrence, N. Y.

Application December 16, 1940, Serial No. 97,361

Term of patent 3½ years

To all whom it may concern:

Be it known that I, Harvey E. Kivelson, a citizen of the United States, residing at Lawrence, Long Island, in the county of Nassau, State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, as shown.

HARVEY E. KIVELSON.
